ENVELOPE CONTAINED MERCHANTISE DISPLAY STAND

Lora McGraw, San Fernando, Calif., assignor to Glen Raven of California, San Fernando, Calif., a corporation of California

Application July 21, 1958, Serial No. 51,868

Term of patent 14 years

(Cl. D80—9)

Fig. 1 is a side elevational view of an envelope contained merchandise display stand, showing my new design;

Fig. 2 is a top plan view; and

Fig. 3 is a transverse, sectional view taken on the line 3—3 of Fig. 1.

I claim:

The ornamental design for an envelope contained merchandise display stand, substantially as shown.
